TAPE CONTROL DEVICE

Walter J. Hanson, Port Chester, N. Y., assignor to
 Pitney-Bowes, Inc., Stamford, Conn., a corpora-
 tion of Delaware

Application July 13, 1946, Serial No. 683,502

3 Claims. (Cl. 101—227)

1

This invention relates to a tape control device which is particularly adapted for use with a metered mail machine wherein impressions are adapted to be printed on either letters or tape.

It is the particular object of this invention to provide means whereby a tape feed roller may be actuated intermittently in a forward and reverse direction while the driving medium rotates continuously in the same direction.

In Patent 2,273,265 a tape feed device is disclosed wherein two rollers frictionally engage either side of the tape and a drive is alternated to effect the drive of one then the other of the two rollers to effect the initial feed of the tape, and after a printing and cutting operation, to return the leading end of the tape to a starting position.

With the mechanism provided by means of this invention, the feed of the tape in both a forward and reverse direction is effected through the control of a single feed roller.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a front view with part in elevation and part in section, showing the tape control mechanism, also the printing drum;

Fig. 2 is an end sectional view taken along the lines 2—2 of Fig. 1, with the guide means removed;

Fig. 3 is an enlarged view of the tape feed and actuating mechanism showing the parts in a home position;

Fig. 4 is a view similar to Fig. 3 and showing the parts in the position they assume during an initial tape advancing operation with the leading end of the tape approaching a printing pick-up position;

Fig. 5 is a view similar to Fig. 3 with the parts in the position they assume during the printing of the tape;

Fig. 6 is a view similar to Fig. 3, showing the parts in the position they assume just prior to tape cutting;

2

Fig. 7 is also a view similar to Fig. 3, showing parts in a tape cutting position;

Fig. 8 is a detail view of the tape feed actuating element;

Fig. 9 is a detailed view of the choke cam and knife actuating element; and

Fig. 10 is a plan view taken along the lines 10—10 of Fig. 6 with the idler pinion removed.

Referring to the drawings in detail, a tape guide track 11 is supported by a bracket 12 and is adapted to direct the tape to the top surface of an impression roller 13. Said impression roller is mounted on a shaft 16, supported by the bracket 12, and is adapted to be driven during each printing cycle of the machine. A printing drum 14 cooperates with said impression roller 13 to effect the printing of a postage impression upon the tape when the leading end of the tape has been advanced to a printing position, and is further adapted to print on letters instead of tape, if desired. Said printing drum and impression roller is adapted to be driven in the usual well known manner. Inasmuch as the present invention is related to tape controlling means, the specification will be restricted to such means, but information concerning the drive, can be found in Patents 2,141,119 and 2,204,972.

When printing is to be effected, the printing drum and impression roller will rotate upon tripping the machine and a pinion 15, fixed to the impression roller shaft 16, will rotate therewith. An intermediate gear 17, carried by a shaft 18, is supported by the bracket 12 and is adapted to be driven by the pinion 15. A segmental actuator gear 19, best shown in Fig. 8, is also fixed to the shaft 18, and thus rotates with the intermediate gear 17. Said segmental gear comprises two gear segments 21 and 22 which are positioned in the same plane, and another gear segment 23, which is offset from the plane of the segments 21 and 22.

A tape feed roller 24 is carried by a shaft 25, which shaft is supported by the bracket 12 and is positioned so that the surface thereof will engage the tape along the lower side thereof. Rotation of said tape feed roller 24 is effected in a clockwise direction to advance the tape when an inside pinion portion 26a of a pinion 26 on said shaft 25 is driven by either of two gear segment portions 21—22 of the tape feed actuator gear 19.

An idler pinion 27 is supported on a stud 28, carried by the bracket 12. As best seen in Fig. 2, said idler pinion 27 includes an inside toothed portion 27a, which is adapted to be engaged by 55 the offset gear segment portion 23, and further

includes an outside toothed portion 27b which meshes with an outside toothed portion 26b of the pinion 26.

Rotation of the impression roller 13 is in a clockwise direction to effect the feed of the tape to the right, as viewed in Fig. 1. Through the drive of pinion 15 and gear 17, the pinion 26 will be driven in a clockwise direction to thus rotate the tape feed roller 24 in the same direction, when either of the two gear segment portions 21 or 22 drive said pinion 26. When however, the offset gear segment portion 23 drives the idler pinion 27, a reverse drive is effected in the tape feed roller 24, the purpose of which will be more fully described later.

Associated with the tape feed roller 24 is an idler roller 29, which roller is carried on a shaft 31, supported by the bracket 12. The tape upon being fed by the tape feed roller 24 is engaged between said roller 24 and idler roller 29.

A choke cam 32 is fixed to the shaft 18, which carries the intermediate gear 17, and is provided with three choke cam surfaces 32a, 32b and 32c. Said choke cam 32 is adapted to effect the choking of the pinion 26 while the tape is being advanced during a printing operation, also when cutting is effected, and again when the mechanism is in a home position. Suitable recesses 33 are provided in the teeth of the pinion portion 26a for this purpose, as best shown in Fig. 10.

Cutting means is provided as indicated at 34, Fig. 7, which comprises a rotary cutter member 35, supported by the bracket 12, and is adapted to rotate within a fixed cutter member 36. Cutting is effected at the cutting edge 38a. At one end of the rotary cutter 35 is a gear segment 37 and meshed therewith is another segmental gear portion 38. The latter is pivotally supported on a stud 39, carried by the bracket 12. An arm 41 extending from the segment gear 38 is adapted to be engaged by an offset portion 42 of the choke cam member 32, when the choke cam is rotated, to thereby effect rotary movement of the rotary cutter 35 when a tape cutting operation is to be effected. Said arm 41 is maintained in the path of the offset portion 42 by the action of a spring 43, which spring normally urges the arm against a stop pin 44.

Reference will now be made to the operation of the device as shown in the several steps illustrated in Figs. 3, 4, 5, 6 and 7. The tape indicated at T, as located in its normal home position, Fig. 3, has its leading end withdrawn below the printing surface of the impression roller 13, and the choke cam surface 32c is in a choking position relative to the recess portions 33 in the teeth of the pinion 26. Assuming that a cycle of operation is to be started to effect printing on tape, the various parts will move in the direction of the arrows, as indicated in Fig. 4, with the segment portion 22 driving the portion 26a of the pinion 26 to effect rotation of the tape feed roller 24 and consequent movement of the tape toward a printing position, as indicated in Fig. 4. The printing drum 14 will have advanced in the meantime, and when a printing die surface 14a thereof reaches the top center of the impression roller, the leading end of the tape will be engaged thereby and driven forward while printing is effected, as shown best in Fig. 5. During said printing operation the choke cam 32b engages the teeth of the pinion 26. To permit free movement of the tape between the tape feed roller 24 and idler roller

29 during the printing operation, a recess is provided, as at 44 in the roller 24, at the position of normal point of contact by the rollers 24 and 29.

5 After the printing operation has been completed, the tape is again advanced, as shown in Fig. 6, to move the leading end thereof through the rotary cutter, which movement is effected when the segmental teeth 21 drive the pinion portion 26a.

15 During the cutting operation, indicated in Fig. 6, the offset portion 42 of the choke cam member 32 will have engaged with the arm 41 of the cutter actuator to effect rotation of the rotary cutter 35 and cause the printed portion of the tape to be severed from the tape strip. During said cutting operation, the choke cam portion 32 is in a choking position relative to recessed teeth 33 of the pinion portion 26a.

20 With the printing and the cutting of the printed portion of the tape completed, the leading end of the tape is returned to its initial home position, which operation is effected when the teeth of the offset segmental portion 23 engage and drive the pinion portion 27a of the idler pinion 27. Through the drive of the pinion 26 by the idler pinion 27, the tape feed roller 24 is driven in a reverse direction, as indicated by the direction of the arrows in Fig. 7, to thus effect the return of the tape to its normal home position, Fig. 3.

Having described the invention what is claimed is:

35 1. In a tape treating device, tape advancing and retracting means comprising a driven roller and an idler roller having peripheral engagement with tape position therebetween, drive means associated with the driven roller including a segmental drive gear, a pinion carried by the driven roller and adapted to be driven by said segmental gear to advance the tape, means to sever the advanced portion of the tape, an idler pinion meshing with the first named pinion, and another segmental drive gear aligned with the idler pinion and rotatable with the first named segment to effect the drive of said idler pinion and thereby effect the drive of the driven roller in a reverse direction for the return of the leading end of the tape to its home position.

50 2. In a tape printing and cutting device, tape advancing and retracting means comprising a driven roller and an idler roller having peripheral engagement with tape positioned therebetween, drive means associated with the driven roller including a segmental drive gear, a pinion carried by the driven roller and adapted to be driven by said segmental gear to advance the printed portion of the tape to a cutting position, an idler pinion meshing with the first named pinion, and another segmental drive gear aligned with the idler pinion and rotatable with the first named segment to effect the drive of said idler pinion and thereby effect the drive of the driven roller in a reverse direction for the return of the leading end of the tape to its home position after cutting the printed portion thereof.

55 3. In combination with a tape printing and cutting device, tape advancing and retracting means comprising a driven roller and an idler roller having peripheral engagement with tape positioned therebetween, drive means associated with the driven roller including a drive gear having two gear segment portions, and gearing including a pinion carried by the driven roller and driven by one segment to advance the tape

from a non-printing to a printing position and by the other segment to advance the tape to a cutting position after printing, an idler pinion meshing with the first named pinion of said gearing, and another segmental drive gear aligned with the idler pinion and rotatable with the drive gear to effect the drive of the idler pinion and thereby effect the drive of the driven roller in a reverse direction to return the leading end of the tape to its non-printing position. 10
